BRIGHTENER COMPOSITION FOR PAPER DERIVED FROM METANILIC AND SULFANILIC ACIDS

Frederick G. Villaume, Martinsville, N.J., assignor to American Cyanamid Company, New York, N.Y., a corporation of Maine
No Drawing. Filed Dec. 15, 1961, Ser. No. 159,791
9 Claims. (Cl. 252—301.2)

This invention relates to an improved brightener composition; to a process for brightening paper therewith; and to the brightened paper thus provided.

The brightener composition of this invention in its acid form is represented by the following:

wherein the R radicals are meta-sulfophenyl radicals, i.e.,

and para-sulfophenyl radicals, i.e.,

the average occurrence of meta-sulfophenyl radicals in the entire composition being between about 0.33 and 0.66 per "DAS" moiety. The symbol "DAS" is used herein to denote the following divalent stilbene radical:

Thus the brightening composition of this invention can be characterized as having para-sulfophenyl radicals and meta-sulfophenyl radicals in a ratio of from about 2:1 to 1:2, the composition in any event being a mixture of at least two of the following three compounds.

2

Compound C

The invention likewise contemplates acid and neutral salts of the foregoing sulfonic acids with inorganic bases such as alkali metal bases, e.g., sodium, potassium and ammonium hydroxides and carbonates.

Heretofore DAS triazine brighteners have been used to neutralize the yellowish tinge of "natural" or untreated paper, thereby giving it an optically bright, i.e., a white, appearance. From a commercial viewpoint, known DAS brighteners are disadvantageous in especially one respect; that is, they do not show their normal full blue fluorescence when applied under acidic conditions such as are encountered in conventional paper making processes. This objection applies to a degree, even to the very components which make up the brightening composition of the present invention. The pH of pulp during mastication, i.e., in the beater operation, often is as low as 4.2 as a result of the use of preacidified pulp, i.e., one in which alum is added before any of the other ingredients, or the use of a white water, i.e., recovered liquor from previous beater operations, as the beater liquor. The disadvantage is thus manifested when the brightener is added to paper pulp before it is converted into sheet paper. Moreover, in some cases these brighteners actually cause additional yellowing of the paper, the degree of yellowing increasing with brightener concentration.

The present invention is based on the discovery that the DAS triazine brightener composition of the present invention is a superior brightener for paper even when applied to the paper pulp during a manufacturing operation. This composition shows a definite advantage in increased pH stability and increased water solubility over other DAS triazine brighteners, even over the component DAS triazines which make up the brightener composition of this invention. They may thus be used in relatively high concentrations to treat pulp under low pH conditions without increasing yellowness in the paper pulp. Thus, for example, a mixture containing equal parts of compound A and compound B, described above, is added at a 0.15% level to a 5% paper pulp having a pH of 4.3 during the beater operation. The resultant paper when viewed under ultraviolet light fluoresces much more strongly than a similar sheet of paper made from paper pulp using the same level of compound A alone, or compound B alone. When viewed in daylight, the paper made with compound A appears definitely yellow, even more yellow than a blank sheet prepared without the brightener. The sheet made using compound B appears just perceptibly yellow, but whiter than a blank sheet.

The sheet prepared with the brightener of the present invention appears strongly whitened, with no trace of yellowness. These comparisons were made on a Hunter whiteness meter, which measures the yellowness and the fluorescence separately and quantitatively. The quantitative results are as follows:

	Yellowness	Fluorescence
Compound A	11.0	8.2
Compound B	7.6	9.5
Brightener of this invention	6.9	10.8

It is apparent that the yellowness of the mixed brightener is less than that of either component alone, and its fluorescence is considerably greater.

It is an advantage of the present invention that the brightener composition thereof may be made in any of several alternative ways. Thus, for example, preformed compound A may be mechanically mixed with preformed compound B in the proper proportions, or alternatively cyanuric chloride may be reacted with diaminostilbene-disulfonic acid, ethanolamine and sulfanilic and metanilic acids, the last two components being in a ratio of between 1:2 and 2:1. However prepared, the brightener mixture within the scope of the present invention shows the aforementioned advantages.

It is a further advantage of the brighteners of the present invention that they are more soluble in water than any of the single component brighteners taken individually. Thus, for example, compound B will form a 15% solution in 25% aqueous triethanolamine but in water alone cannot form even a 15% solution. Contrasted with this, a brightener of the present invention, e.g., having an average of one meta-sulfophenyl radical per DAS moiety will form a 21% solution in water alone. This increased solubility is advantageous in that it allows for the use of more concentrated stock solutions.

While the brightener of the present invention can be applied in the pulp stage, it is not limited to such application. When applied to the paper in sheet form, the application step may be combined either with a finishing or sizing operation by incorporating the brightener into the finishing compositions. The amount of brightener added to the paper is not highly critical, since the usage depends on the desired degree of brightening. In preferred practice a range of 0.01% to 0.2% based on the weight of the dry paper stock is used, since good brightening is obtained economically.

Any conventional paper stock may be brightened by the practice of this invention including paper produced from ground wood pulp, sulfite pulp and other pulps or mixtures thereof.

This invention is further illustrated by the following examples in which parts are on a weight basis.

Example 1

A mixture of 37 parts of 4,4'-diaminostilbene-2,2'-disulfonic acid (in the form of its disodium salt) in 360 parts of water with 270 parts of acetone is cooled to about 5° C. A solution containing 36.9 parts of cyanuric chloride in 200 parts of acetone is added rapidly and after stirring for about 5 minutes, the mixture is neutralized with a 15% aqueous solution of sodium carbonate (gradually over a 30-minute period). To the gelled condensation mixture is then added 17.3 parts of metanilic acid and 17.3 parts of sulfanilic acid. The reaction mixture is heated to 30° C. and then gradually neutralized with sodium carbonate solution (over an overnight period).

After this secondary reaction is completed at 30° C., 36 parts of monoethanolamine are added and the acetone solvent is removed by distillation below 100° C. The mixture is then heated at the reflux temperature for about one hour to complete the final reaction. After clarification a clear aqueous solution of the brightener is obtained.

The aqueous solution may if desired be used as such for application in beater preparation, or the brightener may be isolated in the solid state as the sodium salt by the conventional salting out procedure wherein excess sodium chloride is added to the aqueous solution. This causes precipitation of the solid brightener which is then isolated by filtration.

Example 2

The procedure of Example 1 is followed except that 23.1 parts of metanilic acid and 11.5 parts of sulfanilic acid are used in place of the 17.3 parts of each used therein.

Example 3

The procedure of Example 1 is followed except that 11.5 parts of metanilic acid and 23.1 parts of sulfanilic acid are used in place of the 17.3 parts of each used therein.

Example 4

A beater mixture is prepared using 200 parts of dry bleached sulfite pulp in 4,000 ml. water (making a 5.0% consistency pulp), and 30 ml. of 10.0% alum. Then 0.14 part of the brightener composition of Example 1 is added (0.07% concentration on the dry pulp basis) as a 13.5% aqueous solution. The batch is stirred for one-half hour and handsheets are formed. The sheets are clear white and fluorescent without any evidence of yellow coloration.

When the same experiment is performed using in place of the above brightener composition an equal weight (0.14 part) of a single chemical compound, namely compound A, above, a pronounced yellow coloration of the paper sheet is observed in daylight, and the sheet is unsatisfactory for use as a pure white sheet.

When the same experiment is performed using three times the quantity of brightener composition (namely 0.42 part, or 0.2% on the weight of the pulp) the resultant sheet is still clear white. On the other hand, substitution of 0.42 part of compound A gives a strongly yellow-tinted sheet. Substitution of 0.42 part of compound B gives a sheet with a very slight yellow coloration in daylight.

Example 5

A white water formulation similar to that encountered in actual manufacturing processes is prepared using 4,000 ml. tap water, 10 ml. of commercial sodium silicate solution, 5 ml. of 4.0% rosin and sufficient 10% alum solution to bring the pH to 5.5.

A 5.0% consistency bleached sulfite pulp composition is made up using this white water with 200 parts of dry bleached sulfite pulp and 13 parts of clay. This is stirred 10 minutes and then 70 ml. of 4.0% rosin (pH 7.6) is added. The mixture is stirred an additional 10 minutes, then 0.14 part of the brightener composition of Example 2 is added as a 13.5% solution and the mixture is stirred for another 10 minutes. After adding 68 ml. of 10.0% alum (pH 4.0), the mixture is stirred for an additional 10 minutes and then, after adjusting the pH to 5.5 using sodium aluminate, sheets are formed. A clear white sheet is obtained, which fluoresces under ultraviolet light or daylight, and shows no yellow tinge.

Similar results are obtained using 0.14 part of the brightener composition of Example 3. When the same experiment is performed using the same quantity of compound A the results are unsatisfactory, and the paper shows appreciable yellowing.

Example 6

To 100 ml. of a 6.0% starch solution is added 0.15 part of the brightener mixture of Example 3. The pH is adjusted to about 6 by the addition of aluminum sulfate solution. The resultant starch composition remains white. It is coated on paper sheets, and the sheets dried at 220° F. for 3 minutes. The resulting sheets are con-

siderably whiter than control sheets similarly coated but without addition of a brightener.

When the same experiment is performed using compound A the starch blend is yellow and unsuitable for use in a tub-sizing operation.

I claim:

1. An aqueous brightener composition consisting essentially of water and at least 0.01 weight percent of a member selected from the group consisting of (a) a mixture of at least two of three isomeric compounds represented by the following formula:

wherein the R radicals are meta-sulfophenyl and para-sulfophenyl, the average occurrence of meta-sulfophenyl in the entire composition being between about 0.33 and

10

6. A process of brightening paper which comprises contacting sheet paper, during a finishing operation, with the composition of claim 1.

7. The process of claim 4 wherein the average occurrence of the meta-sulfophenyl radical is 0.5 per diaminostilbene moiety.

8. The process of claim 4 wherein the average occurrence of the meta-sulfophenyl radical is 0.66 per diaminostilbene moiety.

9. A composition of matter consisting essentially of paper and from 0.01% to 0.2%, based on the weight of

the paper, of a member selected from the group consisting of (a) a mixture of at least two of three isomeric compounds represented by the following formula:

0.66 per diaminostilbene moiety, and (b) a salt of the compounds recited in (a) wherein the salt-forming cation is a member selected from the group consisting of sodium, potassium and ammonium.

2. The composition of claim 1 wherein the average occurrence of the meta-sulfophenyl radical is 0.66 per diaminostilbene moiety.

3. The composition of claim 1 wherein the average occurrence of the meta-sulfophenyl radical is 0.5 per diaminostilbene moiety.

4. A process of brightening paper which comprises contacting said paper with a composition of claim 1.

5. A process of brightening paper which comprises contacting paper pulp with the composition of claim 1.

35

40

wherein the R radicals are meta-sulfophenyl and para-sulfophenyl, the average occurrence of meta-sulfophenyl in the entire composition being between about 0.33 and 0.66 per diaminostilbene moiety, and (b) a salt of the compounds recited in (a) wherein the salt-forming cation is a member selected from the group consisting of sodium, potassium and ammonium.
